(57) **CLAIM**

The ornamental design for a lid for a container, as shown and described.

DESCRIPTION

FIG. 1 is a top, front, left perspective view of a lid for a container showing my new design in a condition of use;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings depict portions of the lid for a container that form no part of the claimed design. The

(Continued)

broken lines showing a container in the drawings depict environmental matter that forms no part of the claimed design.
